CLAIM

The ornamental design for a makeup case, as shown and described.

DESCRIPTION

FIG. 1 is a front elevational view of a makeup case showing my new design;

FIG. 2 is a side elevational view thereof from the left of FIG. 1;

FIG. 3 is a side elevational view thereof from the right of FIG. 1;

FIG. 4 is a rear elevational view thereof;

FIG. 5 is a bottom plan view thereof; and,

FIG. 6 is a top plan view thereof.

The oblique line shading represents a reflective metallic surface.

FIG. 4

FIG. 3

FIG. 5

FIG. 1

FIG. 2

FIG. 6
